US00D687902S

(12) **United States Design Patent**
Hunt et al.

(10) **Patent No.:** **US D687,902 S**
(45) **Date of Patent:** **** Aug. 13, 2013**

- (54) **AUTONOMOUS MACHINE FORM**
(75) Inventors: **Timothy S. Hunt**, Cedar Falls, IA (US);
Robert L. Mayfield, Cedar Falls, IA (US); **Mervin P. Kizlyk**, Cedar Falls, IA (US); **Scott Bender**, Cedar Falls, IA (US)
(73) Assignee: **Deere & Company**, Moline, IL (US)

(**) Term: **14 Years**

(21) Appl. No.: **29/380,570**

(22) Filed: **Dec. 8, 2010**

(51) LOC (9) Cl. **21-01**

(52) U.S. Cl.

USPC **D21/533**; D21/548

Primary Examiner — Cynthia M Chin

(57) **CLAIM**

The ornamental design for an autonomous machine form, shown and described.

DESCRIPTION

FIG. 1 is the top perspective view of the autonomous machine form.

FIG. 2 is the left side view of the autonomous machine form.

FIG. 3 is the right side view of the autonomous machine form.

FIG. 4 is the front view of the autonomous machine form.

FIG. 5 is the rear view of the autonomous machine form; and,

FIG. 6 is the top view of the autonomous machine form.

The broken lines represent portions of the article that form no part of the claim.

1 Claim, 6 Drawing Sheets

FIG. 1

FIG. 2

FIG. 3

FIG. 4

FIG. 6
